DESIGN FOR A TIRE

William Edward Hardeman, Solihull, and Samuel Charles Parker, Erdington, England, assignors to Dunlop Tire and Rubber Corporation, Buffalo, N. Y., a corporation of New York

Application December 21, 1946, Serial No. 135,680
In Great Britain July 26, 1946

Term of patent 14 years

(Cl. D90—20)

To all whom it may concern:

Be it known that we, William Edward Hardeman, a subject of the King of Great Britain, resident of Solihull, Warwickshire, England, and Samuel Charles Parker, a subject of the King of Great Britain, resident of Erdington, England, respectively, have invented a new, original and ornamental Design for Tire, of which the following is a specification, reference being had to the accompanying drawings, forming a part thereof.

Fig. 1 is a perspective view, and Fig. 2 is a plan view of a section of a tire showing our new design.

The dominant feature of our new design resides in the sidewall, shown in Fig. 1.

We claim:

The ornamental design for a tire, as shown and described.

WILLIAM EDWARD HARDEMAN.
SAMUEL CHARLES PARKER.
